SEMAUTOMATIC TELEPHONE SYSTEM

Filed June 15, 1928

UNITED STATES PATENT OFFICE

FERNAND PIERRE AUGUSTIN GOHOREL, OF PARIS, FRANCE, ASSIGNOR TO AUTOMATIC ELECTRIC INC., OF CHICAGO, ILLINOIS, A CORPORATION OF DELAWARE

SEMITAUTOMATIC TELEPHONE SYSTEM

Application filed June 15, 1928, Serial No. 285,539, and in France September 23, 1927.

The present invention relates to telephone systems in general, but is concerned more particularly with semi-automatic telephone systems, which systems are characterized by the fact that connections to and from telephone lines are set up by automatic switching equipment under the control of an operator.

More in particular, the present invention concerns itself with a telephone system wherein operators at a central point may control the switching equipment in a plurality of outlying exchanges terminating local-battery magneto lines.

In the invention as illustrated in the accompanying drawing and described herein, the central manual exchange is connected with a remote semi-automatic exchange by means of a number of trunk lines, each of which terminates at the semi-automatic exchange in a switching link comprising two rotary-type switching mechanisms.

According to a feature of the invention, one of the two rotary mechanisms above mentioned operates as a finder switch to find the calling line when a call is made. In case the call is for another line of the same semi-automatic exchange, the operator may control the other switching mechanism to extend a connection to the called line, retaining supervision over the connection through the inter-exchange trunk line.

The one of the two switching mechanisms of a pair that operates as a finder to find a calling line is used also as a connector to extend a connection to a called line under the control of an operator when the operator is extending a connection to a line of a semi-automatic exchange from the outside, and it is a feature of the arrangement that the combined finder and connector switch does not restore at the end of a call, but remains in the position last used, so as to avoid giving the priority of choice to the same lines in all cases, and is returned automatically to its normal position only when taken for use by the operator to complete a call from the manual exchange to a line of the semi-automatic exchange.

A further object of the invention is the

provision of circuit arrangements whereby a subscriber may operate his hand generator to signal the operator at a time when all trunk lines between his exchange and the manual exchange are busy and be signalled when the operator responds and applies ringing current, as she does in each case to cause the connection to be completed at the finder.

A further object of the invention is to provide new and improved circuit arrangements whereby the usual change-over control apparatus in the semi-automatic exchange is eliminated and whereby the provision of dead contact sets for stopping points in the adding-type connectors is unnecessary. For example, when used as an adding-type connector, the usual twenty-five-position mechanism have previously had a normal position and also two dead positions corresponding to 0 and 00 on which the wipers stop in case the line called has a two-digit designation (05, for example) or a three-digit designation (005, for example). By the present arrangement, the operation of the connector remains under the control of the operator until she has finished the setting and has projected ringing current to signal the called station, which latter operation connects up the wipers of the connector and removes it from under the control of further impulses.

It is a further object of the invention to arrange the connections associated with the trunk lines between the manual exchange and the semi-automatic exchange so that the battery which supplies current in the semi-automatic exchange for the operation of the switching apparatus therein is continuously charged from the battery in the manual exchange over each idle interconnecting trunk line.

A feature of the invention is that the relay which is bridged across the semi-automatic exchange end of each trunk and which has its midpoint suitably connected to the battery in the semi-automatic exchange to enable the charging operation to take place, is of the shunt-field type disclosed in Patent 1,544,300, granted June 30, 1925, to Charles J. Erickson, and that the current traverses the wind-

55

95

100

ings of the relay so that the normal charging current through the two windings in parallel does not produce an energization of the relay armature even though there is an unbalanced flow in the two windings, but the relay 5 responds to ringing current transmitted over the two line conductors in series to control the necessary switching function when the operator throws her ringing key.

10 The accompanying drawing shows one embodiment of the invention by means of the usual circuit diagrams.

This drawing shows the trunk line TL connecting the manual exchange with a semi-automatic exchange. The drawing shows in 15 the manual exchange the jack J and other terminating equipment of the trunk line TL and the cord circuit CC at the operator's switchboard.

20 In the semi-automatic exchange the drawing shows the terminating equipment of the trunk line TL, which comprises the main connector and the auxiliary connector, together with the associated relays. In the semi-automatic exchange, there is shown the line circuit 25 LC associated with the line of the local-battery magneto substation SS.

Each of these connectors is of the well known rotary type whose wipers move in a 30 forward direction only and are advanced upon the back stroke of the stepping magnet.

Detailed description

35 A detailed description of the operation of the apparatus shown will now be given. It will first be described how the battery at the manual exchange charges the battery at the semi-automatic exchange over the trunk line TL when this trunk line is idle, it being understood of course, that the semi-automatic exchange battery is similarly charged over 40 any one of the other interconnecting trunk lines that are idle.

Charging the battery at the semi-automatic exchange

It will be noted that there are several battery symbols in the semi-automatic exchange each indicating a battery with the positive 50 pole grounded and the negative pole free. It will be understood, of course, that each of these symbols represents the same battery. It will be noted further that there are several battery symbols in the manual exchange, each indicating a battery with the positive pole grounded and the negative pole free. It will be understood likewise that each of these symbols indicates the same battery. This battery in the manual exchange is designated 55 B1, as distinct from the battery B2 which has its negative pole grounded and the positive pole free for a purpose which will be described hereinafter. In each of the symbols of the battery in the semi-automatic exchange, only one cell is indicated, while in

the manual exchange two cells are indicated in each symbol. This differentiation is merely to indicate that the manual exchange battery is of higher voltage than the semi-automatic exchange battery.

70 Current is normally flowing from the battery in the manual exchange over the two conductors of the toll line TL in parallel, passing from the battery B1, through the lamp L, upper winding of relay 13, armature 122, and the two windings of coil 11 in parallel, to the trunk line. In the semi-automatic exchange, current flows from the two conductors of the trunk line TL in parallel through the two windings of the shunt-field relay 3 in 75 parallel, armatures 61 and 71, right hand winding of shunt field relay 9, and armature 92 of relay 9 to the semi-automatic battery, relay 9 being normally operated as shown.

80 It will be noted that relay 13 in the manual exchange is normally operated, maintaining the circuit of the drop D1 open.

85 A description will now be given of a call from the substation SS to a line reached by way of the manual exchange.

Call from the semi-automatic exchange to the manual exchange

The subscriber at substation SS operates 90 his hand generator G, causing ringing current to be projected over his line to the exchange, operating the bridged relay A. Relay A locks itself to the start conductor at its 95 lower armature, at the same time placing a negative potential on the associated test conductor in the banks of the automatic switches through the winding of the cut-off relay 3.

100 Assuming that the connecting pair shown in the drawing is idle, start relay 6 thereof operates over the start conductor and through resistance R3 in series with the lower winding of relay A. The start relays of any other connecting pairs that happen to be 105 idle also operate, the arrangement being such that the finders of all idle connecting pairs 110 search simultaneously for any calling line. Upon operating, relays 6, at armature 63, closes a circuit from ground at armature 51 through the self-interrupting contacts for the 115 rotating magnet R1 of the main connector, which connector is now to operate as a finder. The magnet R1 operates in a buzzer-like manner to advance the wipers of the main connector step by step in search of the calling line.

120 Assuming that the connecting circuit shown in the drawing is the first to connect with the line of substation SS, test relay 5, which is connected through armature 62 of relay 6 to test wiper T1, operates in series 125 with the lower winding of cut-off relay C, through the upper contacts of relay A. Upon operating, relay 5 opens the circuit of stepping magnet R1 at armature 51 and short circuits relay 6. The presence of resistance 130

R3 in the leg of the start conductor individual to this connecting pair prevents this operation from short circuiting the start relays of the other connecting pairs. Relay 6 is a slow acting relay on account of the copper collar, indicated by the usual symbol, and also because it is short circuited, for which reason it does not fall back immediately. Relay 5, at its lower armature, short circuits its lower winding so as to reduce the test potential on the test conductor of the line of substation SS sufficiently to prevent any other finder from stopping thereon. Relay C of the line circuit LC operates in series with test relay 5 and disconnects the upper winding of line relay at its upper armature; opens the start circuit at its lower armature, and at its inner upper armature it makes a circuit change so that when relay A falls back responsive to the opening of the start circuit the two windings of relay C in series are connected to the test conductor, still further reducing the test potential thereon.

It will be noted that relay 7, one terminal of which is grounded through armature 21 of relay 2, is in series with the stepping magnet R1 and the interrupter contacts thereof through armatures 64 and 63 subsequent to the operation of relay 6. It will be noted further that relay 7, however, is short circuited at armature 51 until relay 5 operates, whereupon relay 7 operates in series with magnet R1. Magnet R1 does not operate at this time on account of the relatively high resistance of relay 7. At armature 73, relay 7 locks itself to the magnet R1 independent of contacts 63 and 64; at armature 72 it shunts armature 62 of relay 6; and at armature 71 it opens the circuit through which the local battery is being charged over the trunk line

TL, this being done only momentarily during the time required for relay 6 to fall back after relay 7 has operated. Relay 6 falls back a moment later and recloses this circuit at armature 61. Relay 9 falls back when the circuit is opened and switches the lower terminal of its lower winding to ground through two paths: One path is through armature 91 and relay 1 and the other path is through contacts normally maintained opened by an armature 92, and through resistance R5 and armature 23.

In the manual exchange, relay 13 falls back when the charging circuit is opened and closes a circuit for the drop D1 which operates to signal the operator.

When relay 6 falls back to reestablish the charging circuit, it closes a circuit through relay 9 and through the two parallel circuits to ground above mentioned, whereupon relay 9 reoperates and reestablishes the previously traced charging circuit. It is assumed that relay 1 does not operate in the time required for relay 9 to pull up and open its circuit.

When the operator notes the operated condition of the drop D1, she inserts the plug of an idle cord circuit, the cord circuit CC, for example, into the jack J to establish a talking circuit with the calling subscriber. At the upper auxiliary contacts of the jack a circuit is closed for relay 12, and at the lower auxiliary contacts of the jack a new circuit over the trunk line TL is prepared from the battery B2 through contacts of the calling device key K. When relay 12 operates, it closes a holding circuit through the lower winding of relay 13 at armature 121, and at armature 122 it disconnects the impulse leg of the trunk line from the battery B1 and connects it through resistance R4 and the above-mentioned auxiliary jack and calling device contacts to the battery B2. Current now flows over the trunk line TL in the reverse direction, causing relay 9 in the semi-automatic exchange to restore and connect up relay 1 and the resistance R5 in parallel. Relay 1 operates and closes a circuit for relay 2 at armature 11 through magnet R1 and the associated interrupter contacts thereof. Relay 2 operates, but it is of sufficiently high resistance to prevent the operation of magnet R1. At armature 23, relay 2 removes resistance R5 from in shunt of relay 1 and places another short circuit around start relay 6. At armature 22, relay 2 locks itself energized independent of armature 11, through armature 82, normal. At armature 21, relay 2 places ground on locking conductor 69, at the same time opening the circuit of relay 7. Relay 7 falls back, but this is without particular result at this time as the function of armature 72 has been taken over by the locking circuit through armatures 24 and 53 in series.

Having plugged in, the operator manipulates the ringing key of the cord circuit CC, thereby projecting ringing current through the jack J and over the trunk line TL through the two windings in series of the bridged relay 3. When current flows through the two windings in series of relay 3, a magnetic flux is set up which passes through the two winding cores in parallel to the armature circuit (not shown), operating the armature to close the springs 31. This establishes a circuit from the grounded conductor 69 through springs 31 for the upper winding of relay 8 and a parallel circuit for the lower winding of relay 10 through the resistance R6. Relay 8 operates at this time, but relay 10 does not operate because its lower winding is short circuited at the associated off-normal contacts of the auxiliary connector. Upon operating, relay 8 locks its lower winding to conductor 69 at contacts 81, at contacts 82 it transfers the locking circuit of relay 2 from magnet R1 of the main connector to magnet R2 of the auxiliary connector preparatory to an operation of the auxiliary connector in case

the call answered is for a local line; and at armatures 84 and 85 completes the talking circuit from the trunk line TL to the line of substation SS, through normally-closed off-normal contacts of the auxiliary connector and the wipers of the main connector. In case the receiver has been replaced at substation SS, the subscriber is recalled by ringing current coming over the trunk line after relay 8 operates.

The operator now converses with the calling subscriber and ascertains the desired number. According to the previous assumption, the calling subscriber desires connection with a subscriber of the manual exchange, from which it follows that the operator completes the connection through the other end (not shown) of the cord circuit CC to the desired line in the usual manner.

When the conversation has been completed, the subscriber at substation SS operates his generator G again momentarily as a ring-off signal, thereby operating the clearing-out drop bridged across the strands of the cord circuit CC. The operator thereupon pulls down the connection. When she does so, the application of current to the trunk line TL from the battery B2 and through contacts of the jack J3, ceases, and relay 12 falls back due to the opening of its circuit at the upper auxiliary contacts of the jack. Relay 12 reconnects the battery B1 to the trunk line TL, whereupon relay 9 is reoperated in series with relay 1 to reestablish the charging circuit and to disconnect relay 1. When relay 1 falls back it short circuits relay 2, thereby closing a circuit through the operated armatures 22 and 82 and through armature 101 for the magnet R2 of the auxiliary connector. The closing of this circuit for the magnet R2 is of course of no utility at this time, but the magnet operates nevertheless. A moment later, relay 2 falls back because it is short circuited and opens the original circuit of the magnet R2 at armature 22, whereupon the magnet falls back and advances the wipers one step. At the same time, relay 2 at armature 21 closes a restoring circuit for the auxiliary connector through the associated off-normal contacts of the auxiliary connector, whereupon the auxiliary connector is restored to normal position.

Local call within the semi-automatic exchange

It will now be assumed that the subscriber at substation SS desires to converse with another subscriber whose line terminates at the semi-automatic exchange and that he obtains connection with the connecting pair shown in the drawing when he makes the call. That being the case, the preliminary operation is the same as described hereinbefore, including the operation which takes place when the operator inserts the plug of her cord circuit

CC into the jack J and applies ringing current to complete the connection to the calling line. It may be pointed out that the condition at the end of the application of the ringing current is that relay 1 is operated over the trunk line TL and that relay 2 is operated through armature 11 of relay 1 from the magnet R1 and is locked through operated armatures 22 and 82 and through armature 101 to the magnet R2 of the auxiliary connector. Relay 8 is operated and is locked to conductor 69 which is grounded at armature 21 of relay 2.

Now, when the operator converses with a calling subscriber and learns that he desires to obtain connection with another line terminating in the semi-automatic exchange, she manipulates the key K so as to associate the calling device CD with the trunk line TL and she then manipulates the calling device in accordance with the digit or digits in the desired number. Assume the number to be 05.

When the operator manipulates the calling device CD in accordance with the digit 0, ten interruptions are produced in the circuit of relay 1, whereupon relay 1 is deenergized ten times momentarily. Each time relay 1 deenergizes it short circuits relay 2, thereby closing a circuit through the operated armatures 22 and 82 and through armature 21 for magnet R2. This circuit is therefore closed ten times momentarily, with the result that the auxiliary connector is advanced ten steps by the operation of magnet R2. At this time it may again be pointed out that since the switchover functions are performed responsive to the application of ringing current and not responsive to the operation of slow acting relays the number 0 may be assigned to the line terminating in the tenth set of bank contacts, which set of bank contacts may also be used as the stopping place for the wipers of the connector when numbers having more than one digit are being called. Relay 2 does not fall back during dialling due to the well-known circulating current through its winding, as it is short circuited instead of having its circuit opened.

When the operator dials the second digit 5, the wipers of the auxiliary connector are advanced five more steps, coming into engagement with the bank contacts (not shown) in which the line 05 terminates.

After dialling the second and last digit in the number, the operator restores her key K and operates her ringing key to project ringing current over the trunk line TL again. This time, the operation of relay 3 results in the closure of an effective circuit through the lower winding of relay 10, on account of the fact that the short circuit has been removed from around this winding at the associated off-normal contacts of the aux-

iliary connector. Relay 10 operates and prepares to lock its upper winding to conductor 69, the other end of its circuit being subsequently completed through the test wiper of the auxiliary connector and the cut-off relay of the called line to battery. The line circuit of the called line is a duplicate of the line circuit LC of the substation SS. The relay corresponding to relay A operates in the line circuit of the called line and completes the circuit of the relay corresponding to relay C, thereby completing the locking circuit of relay 10. The cut-off relay of the called line circuit thereupon pulls up and removes the associated line relay from in bridge of the line.

It will be noted that off-normal contacts of the auxiliary connector have removed shunts from around the condensers in the talking branch leading to the wipers of the main connector. These condensers confine the ringing current for the most part to the intended channels when the operator rings after having set the auxiliary connector on the desired line. This is of utility in case the calling subscriber does not replace his receiver while waiting for the operator to complete the connection. In case the receiver has been replaced, the calling subscriber is recalled by the portion of the ringing current which passes through the above-mentioned condensers.

When the called subscriber responds, conversation may take place. At the end of the conversation, the two subscribers are expected to operate their generators to give the clearing out signal by operating the drop D2 of the cord circuit CC.

When the operator withdraws the plug from the jack J, relay 1 falls back and relay 9 reoperates to reestablish the charging circuit. Relay 1 short circuits relay 2, which relay falls back and closes the restoring circuit of the auxiliary connector at armature 21 through off-normal contacts of the auxiliary connector. The auxiliary connector is restored to normal in the manner hereinbefore pointed out. Relays 8 and 10 fall back when ground is removed from conductor 69 at armature 21.

50 *Call incoming to the semi-automatic exchange*

It will now be assumed that the operator at the manual switchboard receives a call for the line of substation SS at the semi-automatic exchange. Assuming that this call is received on the unshown plug of the cord circuit CC, the operator inserts the shown plug thereof into the jack of an idle trunk line, the jack J of the trunk line TL for example, whereupon relay 12 operates to open the charging circuit and to establish a reversed-current circuit from the battery B2 over the trunk line TL. This results in a deenergization of relay 9 and in the operation of relay 1. When

relay 1 operates under this condition, test relay 5 of the main connector has not been operated and relay 2 is, therefore, short circuited through the back contact of armature 52, off-normal contacts of the main connector, and the back contact of armature 22. The connection of the short circuited relay 2 to the magnet R1 of the main connector through the self-interrupting contacts thereof results in the step-by-step advance of the main connector until the short circuit is removed from around relay 2 at the off-normal contact of the main connector when it arrives in its normal position, whereupon the stepping operation ceases and relay 2 energizes in series with magnet R1 and prepares an operating circuit for the magnet R1 at armature 22, at the same time opening a further point in the restoring circuit of the main connector. At armature 23, the relay 2 renders the start relay 6 non-responsive to control over the start conductor by short circuiting it.

Now, when the operator dials the digit or digits in the desired number, line relay 1 falls back each time its circuit is opened at the calling device CD and closes at armature 11 a circuit for magnet R1 through the operated armature 22 and the armature 82, normal. Magnet R1 responds to these impulses and advances the wipers of the connector into engagement with the line of substation SS.

The operator now applies ringing current to the trunk line TL, operating relay 3 to close a circuit for relay 8. Relay 10, as hereinbefore pointed out, is short circuited at this time and does not respond. Relay 8 responds and locks itself to conductor 69 at armature 81. At armature 83, relay 8 connects the test relay 5 to the test wiper for the first time during this operation, with the result that relay 5 operates in series with relay C as soon as relay A has operated and connected relay C to the test conductor. Relay C disconnects relay A from across the talking circuit.

When the called subscriber responds, he may converse with the calling subscriber through the connection set up through the cord circuit CC and over the trunk line TL.

When the operator receives the usual ring off signal on the drop D2, she pulls down the connection, whereupon relay 9 operates to reestablish the charging circuit and cut off relay 1. Relay 1 falls back in this case and short circuits relay 2, thereby sending an impulse through the operated armatures 22 and 82 and armature 101 to the magnet R2 of the auxiliary connector as hereinbefore described. Relay 2 falls back after a slight interval and opens the circuit just traced, at the same time removing ground from locking conductor 69 and closing the restoring circuit of the auxiliary connector at armature 21. Relay 8 falls back because conductor 69 is ungrounded and test relay 5 falls back when its circuit is opened at armature 83.

Miscellaneous

The resistances R1 and R2 are for the purpose of preventing excess current leakage in case a connected subscriber line is grounded.

5 If desired, they may be replaced by condensers of suitable capacity.

In case one or both conductors of the trunk line TL become grounded to such an extent that the charging current is diverted from the semi-automatic exchange, relay 9 falls back and opens the charging circuit to prevent the battery in the semi-automatic exchange from discharging over the grounded trunk line. The grounded condition is indicated in the manual exchange by the glowing of the lamp L.

What is claimed is:

1. In a combined manual and semi-automatic telephone system wherein a trunk line extending from the manual exchange to a semi-automatic exchange terminates at the semi-automatic exchange in a permanently associated finder switch and in a permanently associated connector switch, means controlled over a calling line for operating the finder switch to connect the associated trunk line with a calling line, and means controlled over said trunk line from the manual exchange for setting the permanently connected connector switch on the contacts of a desired called line to complete a desired connection.

2. In a semi-automatic telephone system wherein telephone lines are accessible to a finder switch and also to a permanently associated connector switch, operator-controlled means for setting said connector switch on any accessible line desired by a calling subscriber whose line is connected with by said finder.

3. In a semi-automatic telephone system, a connecting link comprising a permanently paired finder switch and connector switch both having access to the same plurality of subscribers' lines, a control line extending to a control point, means responsive to the finding of a calling line by said finder for signalling the operator at said control point over said control line, and means controlled by an operator at said control point over said controlled line for operating said connector to complete the connection from the calling line found by said finder to a desired called line.

4. In a telephone system, an automatic connector switch having normally disconnected wipers, means under the control of a calling party for transmitting impulses to said connector switch to advance said wipers into engagement with the contacts of a desired line, and means responsive to an application of ringing current to said connector switch to connect up the wipers.

5. In a telephone system wherein connections are completed through the medium of

automatic switching mechanisms, a line having a given designation, another line having the same designation plus an additional designation, and means responsive to the transmission of the respective designations to said automatic switching mechanisms for setting up a connection to either line whose designation is transmitted.

6. In a telephone system employing a connector switch of the "adding" type, means controlled over a calling line for advancing said adding-type connector and for bringing it to rest on a plurality of lines successively, and means responsive to an application of ringing current to said connector switch after the control thereof has been fully exercised for causing said switch to complete a connection from the calling line to the desired called line only.

7. In a telephone system employing automatic switching mechanism, a finder switch having access to a plurality of lines and arranged to stand normally in any arbitrary position, means including a trunk line extending to said finder for seizing said finder as a connector to complete a connection to a desired one of the lines to which the switching mechanism has access, and means responsive to the seizure of said finder under this condition for advancing it to a predetermined position preparatory to its operation as a connector.

8. In a telephone system wherein connections from calling lines are set up through automatic switching equipment, magneto substations on said calling lines, means responsive to an application of ringing current to a calling line from a magneto substation for operating automatic switching apparatus to set up a connection between the calling line and a switching point, and means for signalling the calling station by ringing current to inform him that the connection is set up.

9. In a semi-automatic telephone system wherein connections are set up from calling magneto lines to a manual switchboard through automatic switching equipment, means responsive to an application of ringing current to the semi-automatic exchange from a calling magneto line for setting up a connection from the calling line to said manual switchboard, and means for signalling the calling subscriber by means of ringing current transmitted from said manual switchboard when the operator responds.

10. In a telephone system, a trunk line extending from a manual switchboard in one exchange to a second exchange, a storage battery in the second exchange, circuit connections for charging the storage battery in the second exchange over said trunk line from a current source in the first named exchange, means responsive to the taking for use of said trunk line in the second exchange for

stopping the flow of charging current over said trunk line, and means responsive to the cessation of charging current over said trunk line for signalling the operator at said manual switchboard.

11. In a telephone system, a trunk line connecting two exchanges and arranged to be used for talking purposes, a storage battery in the second exchange arranged to be charged by a current flow over said trunk line from a current source in the first exchange when the trunk line is not in use for talking purposes, and means including a switching device in the second exchange operative responsive to a shunting of the charging circuit over said trunk line for disconnecting the storage battery in the second exchange from the charging circuit so as to prevent a discharge of the said storage battery.

12. In a telephone system, a trunk line connecting two exchanges and arranged to be used for talking purposes, a storage battery in the second exchange arranged to be charged by a current flow over said trunk line from a current source in the first exchange when the trunk line is not in use for talking purposes, means including a switching device in the second exchange operative responsive to a shunting of the charging circuit over said trunk line for disconnecting the storage battery in the second exchange from the charging circuit so as to prevent a discharge of the said storage battery, and means for automatically reestablishing the charging circuit through said storage battery when the shunt is removed.

13. In a telephone system, two exchanges, automatic switching mechanism in the second exchange, a storage battery in the second exchange, a source of charging current of one polarity in the first exchange for charging the storage battery in the second exchange over said trunk line, a source of operating current of a different polarity in the first exchange, means responsive to the connection of the charging source to said trunk line for switching the trunk line into connection with said storage battery so that the storage battery is charged over the trunk line from the charging source in the first exchange, and means responsive to the substitution of the operating source for the charging source for disconnecting the trunk line from the storage battery and for preparing an operating circuit for the automatic switching mechanism.

14. In a telephone system, a trunk line, a relay having two windings wound on the separate parallel cores and a single armature-return magnetic circuit, said windings being connected in series with each other and in bridge of said trunk line so that current impressed on said windings from across said trunk line results in a parallel magnetic flow through the two cores of the relay to attract

the armature, and a circuit over the two conductors of the trunk line in parallel through the junction of said windings and a separate return, whereby the relay responds only to current flowing from one line conductor to another and not to current flowing in the last mentioned circuit even though the current flow in the two conductors is unbalanced.

In witness whereof, I hereunto subscribe my name this 24th day of May, A. D. 1928.

FERNAND PIERRE AUGUSTIN GOHOREL.
